US0D1093877S

(12) United States Design Patent (10) Patent No.: US D1,093,877 S
(45) Date of Patent: * Sep. 23, 2025

(54) HOLOGRAPHIC SCREEN INTELLIGENT SKIPPING ROPE

(71) Applicant: Fan Yang, Xintai (CN)

(72) Inventor: Fan Yang, Xintai (CN)

() Term: 15 Years

(21) Appl. No.: 29/852,184

(22) Filed: Sep. 4, 2022

(51) LOC (15) Cl. 21-02

(52) U.S. Cl.

USPC D21/672

(58) Field of Classification Search

USPC D21/672, 684, 662, 694
CPC ... A63B 5/20; A63B 2220/17; A63B 2225/74;

A63B 5/205

(57) CLAIM

The ornamental design for a holographic screen intelligent skipping rope, as shown and described.

DESCRIPTION

FIG. 1 is a front perspective view of a holographic screen intelligent skipping rope, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
